(57) **CLAIM**

The ornamental design for a display screen or portion thereof with icon, as shown and described.

DESCRIPTION

FIG. 1 is a front view of a display screen or portion thereof with icon, showing our new design; and, FIG. 2 is a front view thereof, in which a display device in broken lines is provided to illustrate an example environment. The broken lines represent a boundary of the claim and form no part of the claimed design.
